US00D959918S

(12) **United States Design Patent** (10) Patent No.: **US D959,918 S**
(45) Date of Patent: ** Aug. 9, 2022

(54) **CONTAINER**(71) Applicant: **YETI Coolers, LLC**, Austin, TX (US)(72) Inventors: **Dustin Bullock**, Austin, TX (US); **John Loudenslager**, Austin, TX (US); **John Fritz**, Austin, TX (US); **Michael Christopher Cieszko**, Austin, TX (US); **Andrew J. Winterhalter**, Austin, TX (US)(73) Assignee: **YETI Coolers, LLC**, Austin, TX (US)(***) Term: **15 Years**(21) Appl. No.: **29/737,275**(22) Filed: **Jun. 8, 2020****Related U.S. Application Data**

(63) Continuation of application No. 16/218,089, filed on Dec. 12, 2018, now Pat. No. 10,766,672.
